DRIVING MECHANISM

Romeo M. Nardone, Teaneck, N. J., assignor to
Joseph J. Mascuch, Maplewood, N. J.

Application August 19, 1948; Serial No. 45,040

5 Claims. (Cl. 192—.02)

1

This invention relates to driving mechanism, and particularly to motor drives for developing high torque for actuation of a unit to be moved occasionally between two extreme positions, such as the under-carriage, or landing gear, of aircraft. Such a drive commonly includes a reversible electric motor, a reduction gear train, a load-limiting clutch, a normally disengaged jaw clutch, and electro-magnetic means for moving the jaw clutch to the engaged position, and holding it engaged, for the duration of the operating cycle.

An object of the present invention is to provide a novel inter-relationship of the component parts of a driving mechanism of the character indicated, with all moving components rotatable or reciprocable upon a single axis, which single axis is also the focal line about which all stationary components of the mechanism are symmetrically disposed and supported.

Another object of the invention is to construct and inter-connect the clutch and clutch engaging components of the mechanism in such manner as to greatly simplify the procedure for initially adjusting the setting and travel distance through which the clutch is to move, for the engaging and disengaging operations; the said construction and inter-connections also being such as to insure that, once such adjustment has been made, the clutch action will be positive and uniform upon each occasion of use.

Another object of the invention is to provide, in a motor-driven, solenoid-shifted clutch assembly, a novel co-axial disposition of all motor, solenoid, and clutch parts, including all components of the clutch shifting mechanism; there being no bell-cranks, levers, or rocking elements operating in off-center locations, as in most devices heretofore employed.

These and other objects of the invention will be apparent upon reference to the accompanying drawing and the following description of the preferred embodiment; it being understood that said drawing and description merely exemplify the invention without attempting to define its scope or limits; the scope and limits being indicated only in the appended claims.

In the drawing the extreme ends of the motor field yoke are shown at 6 and 7, the central portion being broken away. The commutator end of the motor armature is indicated at 8, and the two end portions of the armature shaft at 9 and 10. The field yoke 6, 7 includes an end rim 11 fitting into a circular recess in housing section 12, which housing section combines with housing section 13

2

to enclose the gear train 14 and the clutch assembly 15. A flange 16 on housing section 13 has a series of holes 17 to receive bolts (not shown) by which the complete mechanism is concentrically supported about its central axis. Field yoke 6, 7 also includes an end wall 18 to which is attached (as by bolts 19) the supporting plate 20 of the solenoid assembly, the latter being enclosed in end cap 22 secured to the plate 20 by screws 23. This solenoid assembly has certain features of novelty in its construction, as do also the clutch assembly 15 and the operating connections therebetween, as will now be described.

Passing through the hollow armature shaft 9, 10 is a rod 24 having threaded ends 26 and 27 for reception of correspondingly threaded elements 28 and 29, respectively; the element 28 being an adjustable nut forming the operative connection (in one direction) between the rod 24 and the shiftable clutch element 15, while the element 29 is an adjustable magnetic core of the solenoid assembly, normally urged away from fixed magnetic core 30 by a spring 31 but movable toward said core 30 upon passage of current to solenoid winding 32. Core 29 is formed with a slot 33 in its end surface, and upon insertion of a suitable tool in said slot the core 29 may be turned in relation to rod 24, thereby automatically adjusting and fixing the over-all distance between the core 29, on the one hand, and the engaging face of the clutch element 15 on the other; there being no end play possible between the rod 24 and the clutch 15, once such adjustment is effected, because ball-bearing assembly 34 forms a positive thrust-transmitting connection between the rod and clutch in both directions of clutch shift. It will be understood that the over-all distance will be properly adjusted after the complete unit has been mounted, that is, the core 29 will at that time be turned up, or turned off, on rod 24, the proper distance to insure full, positive meshing action between clutch element 15 and the mating clutch element (not shown) of the mechanism to be actuated. Following completion of such adjustment, the covering caps 22 and 35 are attached, and the unit is thus completely assembled.

The driving connections from armature shaft 9, 10 to the clutch 15 include a pinion 36 keyed to said shaft, as indicated at 37; a pair of planetary gears 14, a stationary ring gear 38 constituting the reaction, or orbital, element of the planetary train, a two-part cage or spider 39, 40 carrying the gears 14 and rotating therewith about the central axis of shaft 9, 10; a cylinder or

"barrel" 41 bolted to the spider, two sets of inter-leaving friction discs 42, 43, and a sleeve 44 splined internally to the rear portion 45 of clutch 15, and externally to be driven by the discs 43; the discs 42 being in registry with the internal splines of the barrel 41. An annular plate 46 is threaded into the end of the barrel 41 to adjust the pressure on the discs 42, 43, and thus control the load, or torque-transmitting capacity of the unit. Ball-bearing assemblies 47 and 48 support shaft 9, 10 in end walls 12 and 18, respectively.

The magnetic circuit of the solenoid assembly includes, in addition to the two core pieces 29 and 30 above described, a pair of magnetic end plates 49 and 50 held in properly spaced relationship by the intervening magnetic sleeve piece 51 whose circular end sections 52 and 53 are turned in to over-lap and thus retain all three elements in position; the core-piece 30 being similarly secured to end plate 49 by staking its end section 54 against the tapered central opening in the plate. Plate 49 is in turn secured to the over-all supporting plate 20 by screws 55. Registering passages through plates 20 and 49, as well as end wall 18, permit lead 56 to be brought through these passages, so that current may be supplied to the solenoid winding 32 by way of one of the motor terminals (not shown) to which the supply end of lead 56 connects, the delivery end of the lead being indicated at 57, which is the point of connection with one end of the winding 32. The other end of winding 32 is connected to terminal 58, which is grounded through the housing. An inner sleeve 59 separates the winding 32 from the core pieces 29 and 30, and forms a cylindrical guide or bearing facilitating reciprocal movement of the core piece 29. This inner sleeve 59 is first secured to the insulating terminal block 60 by flaring its inner end against the block, while the outer end of the sleeve is similarly staked over the end plate 50, after the latter has been secured within the end section 53 of outer sleeve 51. It will be noted that this assembly is effected without the use of screws or the like, except for the attachment of end plate 49 to the over-all supporting plate 20, and the attachment of cap 35.

In operation, the closing of the motor energizing circuit will result in simultaneous current flow to solenoid winding 32, by way of lead 56. This simultaneous energization of the motor and solenoid will produce concurrent rotation and forward (axial) travel of the clutch element 15 into operative engagement with the mechanism to be actuated, the direction of rotation depending upon the relative directions of current flow in the motor armature and field. When the mechanism to be actuated has moved through its full cycle the motor circuit is re-opened; and, as re-opening of the motor circuit will automatically stop the flow of current to solenoid winding 32, the solenoid spring 31 now becomes effective to return the clutch element 15 to the disengaged position illustrated, and to hold it in such disengaged position until the next cycle of operation is initiated. Such next cycle of operation will involve a flow of current in the opposite direction in either the armature or field of the motor, to reverse its direction of rotation, but flow of current to solenoid winding 32 will again take place in the same direction and manner as before, producing the same clutch operation as above described.

What I claim is:

1. In apparatus of the class described, a ro-

tatable and axially shiftable clutch element, means including a motor for rotating said clutch element, said motor having an end wall centrally and eccentrically apertured, a rod passing through the central aperture in said motor wall for positive axial connection with said clutch element, to shift the latter axially, means for shifting said rod axially, while at the same time holding it against rotation, and means passing through the eccentric aperture in said motor wall to energize said shifting means.

2. Apparatus as defined in claim 1, wherein said rod shifting means includes a solenoid mounted on said motor wall, said solenoid having its magnetic circuit concentric with said rod.

3. In apparatus of the class described, a rotatable and axially shiftable clutch element, means including a reversible electric motor having a hollow armature shaft in axial alignment with the clutch element, and a gear train driven by said armature shaft and responsive to the direction of travel thereof, said gear train being drivably coupled to the clutch element so as to transmit thereto a clockwise or counter-clockwise rotation as desired, a rod passing through the hollow shaft, means for establishing a positive axial thrust connection between said rod and the clutch element in each direction of axial movement of said rod, and clutch shifting means remote from the clutch consisting of a solenoid assembly including co-operating magnetic elements, means for securing one of said magnetic elements against rotation, means for moving the second of said magnetic elements axially into engagement with the first magnetic element, whereby both magnetic elements are secured against rotation and means for fastening said rod within the second magnetic element to shift axially therewith and to be restrained from rotation by reason of the restraint upon the said second magnetic element.

4. Apparatus as defined in claim 3, wherein said clutch element, shaft, rod, and regulating means are all operable on the central axis of said apparatus.

5. Apparatus as defined in claim 3, wherein said connection-establishing means includes a ball-bearing assembly concentric with said rod and clutch element, and means for preventing relative axial displacement between said rod and clutch element.
